Primary Examiner—James Gandy*Assistant Examiner*—Stacia Sinuik*Attorney, Agent, or Firm*—Locke Purnell Rain Harrell[57] **CLAIM**

The ornamental design for cargo carrier, as shown and described.

DESCRIPTION

FIG. 1 is an enlarged perspective view of a cargo carrier showing my new design;

FIG. 2 is a rear elevational view of a cargo carrier;

FIG. 3 is a side elevational view thereof, the opposite side being a mirror image of the view of FIG. 3;

FIG. 4 is a front elevational view thereof;

FIG. 5 is a top plan view thereof; and,

FIG. 6 is a bottom plan view of my cargo carrier.
